Patented Feb. 22, 1927.

UNITED STATES PATENT OFFICE.

LEVIN FAUST, OF ROCKFORD, ILLINOIS, ASSIGNOR TO ROCKFORD STEEL FURNITURE COMPANY, OF ROCKFORD, ILLINOIS, A CORPORATION OF ILLINOIS.

IRONING BOARD.

Application filed November 19, 1924. Serial No. 750,763.

This invention relates to ironing boards and has reference more particularly to ironing boards of that type which are foldable into and out of a cabinet mounted on or in

- 5 a wall.
- Among the objects of the invention are, to provide an improved ironing board of the type referred to wherein the inner or heel end of the board shall be strongly supported
- 10 in the cabinet through the agency of a vertically sliding support or apron engaged with ways in the cabinet permitting the heel portion of the board to rise and fall as the board is folded outwardly and inwardly, to
- 15 provide an improved construction of ironing board wherein the board may be swung angularly in a horizontal plane when lowered to working position and securely locked and held at its inner or heel end when
- 20 in such angularly shifted position, to provide a light, durable and strong construction of board and cabinet wherein all of the parts excepting the board itself are of metal, to provide a construction including
- 25 the use of a vertically sliding support or apron in the cabinet for the heel end of the board, said apron being adapted to resist twisting or torsional strain when the lowered board is swung to one side, to pro-
- 30 vide an improved structure and mounting of board brace adapted to permit the angular side adjustment of the board without impairment of its function as a supporting strut, and, generally, to provide an im-
- 35 proved and economical structure of folding ironing board of the cabinet type.

These and other objects and attendant advantages of the invention will be apparent to persons skilled in the art as the same becomes better understood by reference to the following description, taken in connection with the accompanying drawing in which I have illustrated one practical and approved embodiment of the invention, and wherein—

- 40 Fig. 1 is a front elevation of the cabinet and board in folded position, omitting the door of the cabinet;
- 45 Fig. 2 is a front elevation of the cabinet and board in folded position, omitting the door of the cabinet;

Fig. 2 is a horizontal section through the cabinet, showing the board in lowered or working position and also showing in dotted lines an angular position of the board; and

50 Fig. 3 is a longitudinal vertical section of Fig. 1, also showing in dotted lines the lowered position of the board.

55 Referring to the drawing, 5 designates as

an entirety a rectangular sheet-metal cabinet of a size to house the ironing board and its supporting mechanism and preferably formed on its outer face with a marginal flange or molding 6, whereby the cabinet is 60 adapted to be neatly fitted into a suitable wall opening. On the inner sides of the longitudinal side walls of the cabinet, near their lower ends, are mounted slideways each conveniently formed by a pair of parallel 65 spaced angle strips 7. Slidably mounted in these ways is a sheet-metal apron 8, the vertical edges of the latter being engaged with the ways formed by the angle strips 7. At the top of the vertical slideways are stops 9 70 (Fig. 2) which limit the upward sliding movement of the apron 8, and prevent the inner end or heel of the ironing board from tipping upwardly under the pressure of the work thereon. Across the upper edge of 75 the apron 8 is an angle strip 10 which provides an outwardly projecting horizontal flange which the part 12 on the ironing board is arranged to overlie when the board is extended in its operative position. The 80 flange serves to stiffen the apron in an obvious manner. To the upper edge of the apron 8 is flexibly secured, as by hinges 11, the part 12 which is in the form of a sheet-metal heel plate preferably formed with a 85 rounded substantially semi-circular upper or outer edge, as shown.

Pivoted to the underside of the heel plate 12 by a vertical pivot bolt 13 is the inner or lower end of the ironing board 14. 90 Hinged to the under side of the ironing board by horizontal pivot pins 15 are a pair of downwardly convergent metal brace rods 16, together forming a supporting strut for the board. The lower ends of these brace 95 rods are supported on the bottom wall of the cabinet and they are hinged by a horizontal pivot pin 17 to an eye bolt 18 that itself is vertically pivoted in the bottom wall of the cabinet so as to be capable of turning in 100 a horizontal plane.

The ironing board 14 is additionally attached to the heel plate 12 by means of a clamp screw 19 in the ironing board extending upwardly through an arcuate slot 20 in the heel plate 12. When the board is lowered to working position, as shown in Fig. 2 and by dotted lines in Fig. 3, the pin 19 and slot 20 permit the board 14 to 105 be swung angularly in a horizontal plane to 110

an extent limited by the slot 20 and secured in any set position by tightening up the clamp screw 19. The heel plate 12 is preferably provided on its upper side with a pair of oblique ribs 21 which serve to stiffen the heel plate and also form convenient rests for the flat-iron when not in use.

The cabinet is designed to be equipped with the usual door (not shown) which may be hinged at the points indicated at 22 in Fig. 1, and it will be observed by reference to Figs. 1 and 3 that the apron 8, in the folded position of the board, is sufficiently above the bottom wall of the cabinet to permit the latter to be used as a shelf for the flat-irons when not in use.

Figs. 1 and 3 show the board in idle position within the cabinet and completely encased and concealed by the latter when the door of the cabinet is closed. To bring the board into working position it is necessary only to open the door and draw the upper end of the board outwardly and downwardly. During this operation, the board swings outwardly on the upper ends of the braces 16 as moving fulcrums. The lower end of the board at the same time swings upwardly, the sliding apron 8 rises in its guides until the upper ends of its vertical edges are arrested by the stops 9 and the heel plate 12 rises and simultaneously folds downwardly to the horizontal position shown in Fig. 2 and by dotted lines in Fig. 3. The brace rods 16 swing outwardly on the pivot 17. By making the board supporting and guiding parts of metal of sufficient weight and strength, the board is adequately supported in working position by the braces or struts 16 and the stops 9, without requiring the usual hinged leg on the under side of the free or outer end of the ironing board. When the board is to be replaced within the cabinet, this is done by simply elevating and pushing inwardly the upper end of the board, whereby the latter swings on the upper ends of the braces 16 and the latter at the same time swing inwardly with the board to the position shown in full lines in Figs. 1 and 3, wholly within the cabinet.

I am aware that cabinet ironing boards fixedly hinged at their inner ends to the cabinet and adapted to be swung outwardly of the latter are broadly old and known; and also that the use of a hinged support to which the lower end of the ironing board is pivoted so as to permit the latter to be adjusted angularly in a horizontal plane, when lowered, is also known. So far as I am aware, however, a construction such as I have herein disclosed wherein the lower end of the ironing board, or a heel plate attached to the latter to afford angular adjustment of the ironing board, is hinged to a vertically slidable support or apron within the cabinet, is new; and this feature,

when combined with a pivoted brace or strut for the ironing board capable of swinging inwardly and outwardly of the cabinet and also laterally of the latter, presents practical advantages in respects of simplicity, strength and flexibility not possessed by known devices of this character.

While I have herein shown and described one practical embodiment of the principle of the invention it is manifest that the specific details of structure and arrangement may be considerably varied without departing from the principle of the invention or sacrificing any of the advantages thereof. Hence, I do not limit the invention to the exact construction shown, but reserve such variations and modifications as fall within the spirit purview of the appended claims.

I claim—

1. In a foldable ironing board of the type described, the combination of a cabinet having slideways therein, stops at the upper ends of said slideways, a vertically sliding member mounted in said slideways, an ironing board flexibly connected to said member to swing inwardly and outwardly of said cabinet and pivoted to swing on a vertical axis relative to said member when in extended position, and a strut pivoted at its upper end to the under side of said ironing board and at its lower end having a universal pivot connection to the bottom wall of said cabinet.

2. In a foldable ironing board of the type described, the combination of a cabinet having slideways on the inner side walls thereof, stops at the upper ends of said slideways, an apron mounted in said slideways, a heel plate hinged to said apron, an ironing board pivoted to said heel plate upon a vertical axis, and a strut on the under side of said ironing board.

3. In a foldable ironing board of the type described, the combination of a cabinet having slideways on the inner side walls thereof, stops at the upper ends of said slideways, an apron mounted in said slideways, a heel plate hinged to the upper end of said apron, an ironing board pivoted to said heel plate upon a vertical axis, and a strut pivoted at its upper end to the under side of said ironing board and at its lower end of the bottom wall of said cabinet.

4. In a foldable ironing board of the type described, the combination of a cabinet having slideways on the inner opposed side walls thereof, stops at the upper ends of said slideways, an apron mounted in said slideways, a heel plate hinged to said apron and formed with an arcuate slot in the outer portion thereof, an ironing board pivoted to the inner portion of said heel plate and equipped with a clamp screw engaged with said slot, and a strut on the under side of said ironing board.

5. In a foldable ironing board of the type

described, the combination of a cabinet having slideways on the inner side walls thereof, stops at the upper end of said slideways, an apron slideable in said slideways, a heel plate hinged to the upper end of said apron, an ironing board pivoted to said heel plate for angular adjustment edgewise relative to the latter, means on said heel plate and ironing board for securing the latter in adjusted 5 position angularly, and a strut on the under side of said board for supporting the same. 10

6. In a foldable ironing board of the type described, the combination of a cabinet having slideways on the inner opposed side walls thereof, stops at the upper ends of said slide- 15

ways, an apron mounted at its sides in said slideways, a heel plate having its inner end hinged to the top of said apron and formed with an arcuate slot in the outer portion thereof, an ironing board pivoted to the inner portion of the heel plate with relation to which pivot the slot is concentric, a clamp screw extending through the slot of the heel plate and carried by the board to secure the board in adjusted angular relation relative 20 to the plate, and a brace pivoted to the under side of the board and connected to the bottom of the cabinet for vertical pivoting and horizontal swinging movement.

LEVIN FAUST.

described, the combination of a cabinet having slideways on the inner side walls thereof, stops at the upper end of said slideways, an apron slideable in said slideways, a heel plate hinged to the upper end of said apron, 5 an ironing board pivoted to said heel plate for angular adjustment edgewise relative to the latter, means on said heel plate and ironing board for securing the latter in adjusted 10 position angularly, and a strut on the under side of said board for supporting the same. 15 6. In a foldable ironing board of the type described, the combination of a cabinet having slideways on the inner opposed side walls thereof, stops at the upper ends of said slide-

ways, an apron mounted at its sides in said slideways, a heel plate having its inner end hinged to the top of said apron and formed with an arcuate slot in the outer portion thereof, an ironing board pivoted to the inner portion of the heel plate with relation to which pivot the slot is concentric, a clamp screw extending through the slot of the heel plate and carried by the board to secure the board in adjusted angular relation relative 20 to the plate, and a brace pivoted to the under side of the board and connected to the bottom of the cabinet for vertical pivoting and horizontal swinging movement.
